UNITED STATES PATENT OFFICE

HANS ZIMMERMANN, OF BERLIN-PANKOW, GERMANY

MOVABLE WEIR WITH HINGED TOP FLAP OR HEAD

Application filed November 13, 1926, Serial No. 148,282, and in Germany November 27, 1925.

The invention relates to movable weirs with hinged top flaps or heads, and its object is to provide a simplified and improved construction of weir and actuating means.

It is known, for instance in sluice weirs with flaps for regulating ice and depth of water, to actuate the flap by lifting means driven by the main operating mechanism of the weir, but it has been the practice to employ 10 separate means for lifting the sluice and the flap.

Now, in order not to impede the movement of the flap, the lifting means for the sluice must act from behind (viewed in relation to 15 the aperture of the weir) the side bracket serving to make a tight joint between the side of the flap and the pier slot in which the sluice is guided. On the other hand, the lifting means for the flap has always been arranged 20 in front of the side bracket, as the flap extended only as far as said bracket.

In contrast with known arrangements, the present invention provides a single or common lifting means for the weir or sluice and 25 the flap, said means lying sheltered in the pier slot. At the same time, care is taken to prevent the flap from being loaded by the weight 30 of the weir or sluice, although the lifting means acts directly on the flap.

Constructional forms of the invention as applied to sluice weirs are illustrated by way 35 of examples in the accompanying drawings to which reference will now be made.

Fig. 1 is a section through the pillar slot of 40 a sluice weir (viewed from the head water side) intended to be lifted with the flap in the erect position.

Fig. 2 is a cross section through the weir showing the flap in the erect position.

45 Figs. 3 and 4 represent a like cross section, but with the flap lowered and in an intermediate position respectively.

Fig. 5 shows the application of the invention to a weir intended to be lifted when the flap is let down.

Fig. 6 shows a modification of the arrangement according to Fig. 5.

Referring first to Figs. 1-4 it will be seen 50 that the sluice 1 carries, at each side, a sector-like bracket 2 which makes a tight lateral

joint with the hinged head or flap 3. Attached to the flap 3 is an operating bar 4. This bar projects into the pier slot 5 above the side bracket 2 and is connected with chain lifting means 6. An extension 7 is connected 55 to the end of the said lifting means 6 in such a manner that the tension in it for lifting the sluice directly acts upon the suspension pin 8, this extension 7 being arranged in such a manner as not to prevent a rotation of the 60 flap 3 around an axis which is not in alignment with the axis of the pin 8. Said lifting means is actuated through a single chain wheel 9 arranged above the pier slot, whereas hitherto a second actuating wheel was usually 65 required for actuating the flap.

This new arrangement works in the following manner:

If the sluice 1 is to be lifted out of the position of repose (Fig. 1), the actuating wheel 70 9 is turned in a direction to shorten the lifting means 6, whereupon the flap 3 is first 75 lifted into the erect position by reason of the connection of said means with the bar 4. During this movement the extension 7 of the 80 lifting means turns freely upwards, the flap bar 4 sliding, for example, in a longitudinal slot 10 in said extension (see Fig. 4). The bar 4 describes an arc 12, of radius R, about the 85 rotational axis 11 of the flap, and the upper bearing surface of the extension of the lifting means describes an arc 13, of radius r, about the pin 8. The upper point of intersection 90 of these two arcs (see Figure 2) indicates the position at which, when attained, the tractive force of the lifting means 6 is transmitted, through the member 7, to the suspension pin 8 and therefore to the sluice 1, which is not affected while the flap is being raised 95 into the erect position but is thereafter lifted upon shortening the lifting means still further. After the flap 3 is moved to erect position, it is subjected only to the tractive force resulting from the moment of the water pressure thereon, because there are no steps or the like to prevent its freedom of adjustment 100 (see Fig. 2).

As previously stated, Fig. 5 shows the invention applied to a sluice weir intended to be lifted with the flap let down. In this con-

struction, the portion 6^a of the common lifting means that depends from the other side of the actuating wheel, is attached to the flap bar 4.

5 In the embodiment according to Fig. 6, which closely resembles that of Fig. 5, especially favourable conditions with regard to the operating speeds and forces are obtained in that one end of the lifting means is allowed 10 to act directly on the flap and the other end acts on the sluice 1 through the medium of an idle pulley or block tackle or the like. From the chain wheel 9, one end of the chain 6 passes directly to the bar 4 of the flap 3 where- 15 as the other end is attached to a fixed point *f* after being led round an idle pulley *r*, rotatably mounted on the free end of the member 7 that engages the pin 8.

If the chain wheel 9 be turned at a peripheral velocity *v*, it raises or lowers the sluice 1 (according to the direction of rotation) with 20 a velocity $\frac{v}{2}$. On the other hand, the portion 6 of the chain engaging the flap-bar 4 will 25 lower or raise the flap with a velocity *v*, that is to say, twice as fast. The actuating mechanism is subjected to only half the moment of load, since, in view of the distribution of the load between the two portions of the chain, 30 the strain on the chain is reduced, and therefore also a chain wheel of smaller diameter can be used, which means a still smaller loading.

The invention herein described offers, inter 35 alia, the advantage that the attachment pin 8 can be so displaced, independently of the rotational axis of the flap, as to come into alignment with the perpendicular drawn from the centre of gravity *S* of the sluice tan- 40 gentially to the actuating wheel 9. With this arrangement the sluice is not subjected to the action of any tilting force.

As the flap bar 4 projects into the slot 5 of the pier 15, it is desirable (especially in 45 the case of tall flaps) to prevent said bar from striking against the wall 14 of the slot forming the trackway on the tail water side. For this reason it is advisable to slope the track 14 of the sluice as shown in the figures.

50 Instead of a rigid member 7, there may be used a flexible means (for example, a rope or a chain) which is free to sag when relieved of tension.

The use of a common lifting means for the 55 sluice and the flap leads to the simplest construction imaginable, and therefore reduces the prime cost, the expense of attendance and the upkeep of the lifting means, especially when chains are employed. No part of the 60 lifting means is exposed to the flowing water. Owing to the working point of the lifting means being at the outer edge of the flap, a considerable reserve of power is available, especially when the flap is let down. The axis 65 of the flap does not require to pass through

the side bracket and transmit torsional stresses; the position of the lifting means for the sluice is independent of the axis of the flap; and the tractive connection between the lifting means and the sluice is of an extremely 70 simple character.

With the embodiment according to Fig. 6, technical working advantages are obtained in conjunction with economies in the actuating mechanism. High speeds are obtained in 75 respect of the flap, without the necessity for increasing the speed of the driving motor or providing a countershaft.

Obviously the chain 6 may in the construction described be replaced by ropes or other 80 flexible lifting agents.

Having now particularly described and ascertained the nature of my said invention and in what manner the same is to be performed, I declare that what I claim is:—

85 1. A movable weir with hinged top flap, having common means including a driven sprocket and a chain fastened at one end and having its other end attached directly to the flap and extended in attachment also to the weir for turning the flap and lifting the weir on continued actuation after the flap is turned.

90 2. A movable weir with hinged top flap, having common means for lifting the weir and turning the flap, said means comprising a member fastened at one end and attached at its other end directly to the flap at each side of the weir by fastening means on the upper margin of the flap and having an extension thereof attached to the weir, and gearing for winding said member so as to turn the flap and lift the weir on continued winding after the flap has turned to limited position.

95 3. A movable weir with hinged top flap, having common means for lifting the weir and turning the flap, said means comprising a flexible member fastened at one end and having its other end attached directly to the flap at each side of the weir by fastening means on the upper margin of the flap, a link forming an extension of said flexible member pivotally attached to the weir, and means for reeling said member to turn the flap and lift the weir after the flap has reached its limit 100 of turn movement.

105 4. A movable weir with hinged top flap having common means for lifting the weir and turning the flap, said means comprising a flexible member at each side of the weir secured at one end and attached at its other end directly to the flap by fastening means on the upper margin of the latter, a link forming an extension of the flexible member 110 pivotally attached to the weir at a point eccentric with respect to the turning axis of the flap, and means for reeling said member to turn the flap and lift the weir after the flap has reached its limit of turn movement.

115 5. A movable weir with hinged top flap,

having common means for lifting the weir and turning the flap, said means comprising a flexible member at each side of the weir secured at one end and having its other end attached directly to the flap by fastening means on the upper margin of the flap, a link forming an extension of the flexible member pivotally attached to the weir in alinement with the perpendicular passing through the member and the center of gravity of the weir when the latter is raised, and means for reeling or winding said member for turning the flap and lifting the weir after the flap has reached its limit of turn movement.

6. In a movable weir, the combination of a sluice mounted for sliding movement between slotted piers, a top flap hinged to the sluice, side brackets on the sluice making tight lateral joints with said flap, and means for turning the flap and lifting the sluice after the flap has reached a limit of movement comprising a flexible member at each side of the weir having one end fastened and its other end attached directly to the flap by fastening means on the upper margin of the latter projecting into the slots of the pier above said side brackets, said flexible member having an extension attached to the sluice at a point eccentric to its attachment with the flap, together with means for reeling the flexible member in opposite directions.

7. In a movable weir, the combination of a sluice mounted for sliding movement between slotted piers, a top flap hinged to the sluice, side brackets on the sluice making tight lateral joints with the flap, and means for lifting the sluice and turning the flap comprising a flexible member attached directly to the flap at each side of the weir by fastening means on the upper margin of the flap projecting into the slots of the piers above said side brackets and said means having an extension pivotally attached to the sluice for lifting the latter after the flap is turned, together with means for reeling the flexible member.

8. In a movable weir, the combination of a sluice mounted for sliding movement between slotted piers, a top flap hinged to the sluice, side brackets on the sluice making tight lateral joints with the flap, and means at each side of the weir adapted to coordinately lift the sluice and turn the flap, said means comprising a member on the flap projecting into the pier slot above the side bracket, flexible lifting means having attachment to said member, a suspension pin on the sluice projecting into the pier slot, and an extension of said lifting means attached to said pin.

9. In a movable weir, the combination of a sluice mounted for sliding movement between the slotted piers, a top flap hinged to the sluice, side brackets on the sluice making

tight lateral joints with the flap, and means at each side of the sluice adapted commonly to lift the weir and turn the flap, said means comprising a pin projecting from the flap into the pier slot above the side bracket, a link having a slotted end in engagement with the pin and the opposite end pivotally attached to the sluice, a flexible lifting member having attachment to the pin, and means for reeling said member.

10. In a movable weir, the combination of two piers each provided with a slot having an inclined side wall, a sluice mounted for slideable movement between said piers, a top flap hinged to the sluice and adapted to tilt downward toward said inclined walls, side brackets on the sluice making tight lateral joints with the flap, and means at each side of the weir for coordinately lifting the sluice and turning the flap.

11. In a movable weir, the combination of two piers each provided with a slot having an inclined side wall, a sluice mounted for slideable movement between said piers, a top flap hinged to the sluice and adapted to tilt downward toward said inclined walls, side brackets on the sluice making tight lateral joints with the flap, and means at each side of the weir for commonly tilting the sluice and turning the flap, said means including a member on the flap projecting into the pier slot above the side bracket, flexible lifting means having end attachment to said member, and an extension of said lifting means attached to the sluice.

12. In a movable weir, the combination of two piers each provided with a slot having an inclined side wall, a sluice mounted for slideable movement between said piers, a top flap hinged to the sluice and adapted to tilt downward toward said inclined walls, side brackets on the sluice making tight lateral joints with the flap, and means at each side of the weir for commonly lifting the sluice and turning the flap, said means, including a member on the flap projecting into the pier slot above the side bracket, flexible lifting means having attachment to said member, a suspension pin on the sluice projecting into the pier slot, and an extension of said lifting means having attachment to said pin.

13. In a movable weir embodying a sliding sluice with hinged top flap adapted to tilting movement, the combination of actuating means, flexible lifting means at each end of the weir acted upon by said actuating means to commonly act upon said sluice and flap for sliding the former and tilting the latter, each of said lifting means having one end fixed and its other end connected directly to said flap for raising and lowering the latter, together with a block having link connection with said sluice over which an intermediate portion of said flexible means passes for caus-

ing said sluice to slide up and down as said flap is raised and lowered.

14. In a movable weir embodying a sliding sluice with hinged top flap adapted to tilting movement thereon, means for lifting the sluice and turning the flap on its axis comprising in combination, flexible members attached directly to the flap at opposite sides of the weir and having extensions pivotally attached to the sluice at opposite points eccentric to the axis of the flap, and means simultaneously actuating said flexible members so as to tilt the flap and slide the sluice after the flap is tilted.

15. In testimony whereof I have affixed my signature.

HANS ZIMMERMANN.
